UNITED STATES PATENT OFFICE

JEAN ARAS, OF DULUTH, MINNESOTA

DEVICE FOR PLATTING AND MEASURING CURVES

Application filed May 8, 1931. Serial No. 536,042.

The invention relates to the art of plating and measuring curves and has reference more particularly to an adjustable curved ruler.

5 An object of the invention is to provide an improved ruler, protractor or the like, adjustable to different curves, and to provide such devices with means for indicating the degree of curvature in any adjustment 10 of the device out of a straight line.

An additional object is the provision of a device of this character, which will be simple in construction and inexpensive to manufacture, efficient in use, easy to operate and 15 control, and one which will fulfill all requirements of service.

With these and various other objects in view, the invention may consist of certain novel features of construction and operation, as will be more fully described and particularly pointed out in the specification, drawing and claims appended hereto.

In the drawing, which illustrates an embodiment of the device and wherein like reference characters are used to designate like parts—

Figure 1 is a side elevational view of the device constructed in accordance with the present invention;

30 Figure 2 is a side elevational view of the device with the ruler adjusted to form a curve;

Figure 3 is a sectional view taken along line 3—3 of Figure 1;

35 Figure 4 is a sectional view taken along line 4—4 of Figure 1; and

Figure 5 is a sectional view taken along line 5—5 of Figure 1.

40 The device as illustrated comprises a ruler 10 or strip of flexible metal having rigidly secured to its ends end members 12 and 14 respectively, of right angled form. Extending inwardly from the members 12 and 14 are reinforcing strips 16, serving to reinforce the flexible strip 10.

An indicating bar 18 is provided having formed on one face adjacent one end of the same a plurality of indications 20 directly under which are provided numbers for the 45 indications respectively. The construction

forms a scale on the indicating bar 18, the markings 20 showing the degree of curvature which the ruler 10 may assume while the numbers show the value of the degree of curvature. The member 12 is pivotally secured to the left hand end of the indicating bar by means of the rivet stud 22, Figure 3, while at the right hand end the indicating bar is provided with a slide 24 in the form of a channel shaped member adapted to be 55 mounted in adjusted position on the bar by means of the cover 26 and set screw 28 threaded therein. To the slide 24 is pivotally secured the right hand member 14, as shown in Figure 5, so that the ruler 10 can be given 60 a degree of curvature by merely sliding the slide 24 along the indicating bar 18. The end members 12 and 14 are rigidly secured to the under surface of the ruler 10 at the 65 respective ends of the same and with the lower ends of the members pivoted, they will assume a certain angular relationship with the indicating bar 18 for any particular curvature of the ruler 10, but it is to be especially noted that the members will provide a tangent to the curve for any curvature. 70

The normal tendency of the flexible ruler, when the pivoted ends of the same are confined and moved towards each other, is to flex to a greater extent in the middle and to 75 form a parabolical curve rather than a true arc of a circle. In order to correct the curvature of the ruler, since it is desirable at times to secure a true arc, and to sustain the ruler in any adjusted curvature the same is provided with depending braces 29 pivoted to the ruler by means of angle members 30 which are suitably secured to the under surface of the ruler. The lower ends of the braces 29 are connected by pivotal links 32, the links being connected to their particular braces by means of a stud 34 and the winged nut 36. After the ruler 10 has been given the desired curvature, the arc can be more 80 efficiently maintained by holding each link 32 in its adjusted position with respect to its particular brace 29, which is accomplished by means of the stud and winged nut 36. It is to be noted that irrespective of the curvature of the ruler 10 the braces 29 will always 85 90 95 100

assume a vertical position, that is, should the braces be extended they would intersect the bar 18 so as to form right angles. The angular relationship of the links will of course vary for any curvature, but will be substantially parallel to every adjusted portion of the ruler 10.

It is obvious that the improvements in the adjustable curved ruler may be embodied in various forms without departure from the essentials of the invention, the particular arrangement resulting in a simple device which is very valuable to draftsmen and others for ruling curves of large radii. In operation the slide 24 is moved along the bar 18 until the inner edge of cover 26 is in alignment with that particular indication 20 to secure the desired degree of curvature. The set-screw 28 is then tightened to hold the member in position. The links 32 can, during this procedure, be maintained in loose contact with their respective braces and can subsequently be held rigid to the braces by a tightening of the winged nuts 36, which will function to maintain all of the braces and other links in set relationship with the flexible strip or ruler.

It is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

I claim:

1. An adjustable ruler of the character described including a flexible strip, right angular members secured to the ends thereof, an indicating bar, one member being pivotally secured to one end of the bar, a slide adjustably mounted on said bar, means pivotally securing the other member to said slide, and means for maintaining the curvature of the strip in adjusted position including braces pivotally secured to and depending from the strip at spaced points, links connecting the braces, and means for holding the links and braces in adjusted position.
2. An adjustable ruler of the character described including a flexible strip, end members rigid with the ends of said strip, said members comprising right-angled forms, an indicating bar, means pivotally securing one end member to one end of said bar, a slide mounted for movement on the other end of the bar, and a set screw pivotally securing the other end member to said slide, said set screw also serving to adjustably secure the slide on the bar.
3. An adjustable ruler of the character described including a flexible strip, right-angled members secured to the ends thereof, an indicating bar, one member being pivotally secured to one end of the bar, a slide

adjustably mounted on said bar, means pivotally securing the other member to said slide, and means for adjusting the curvature of said strip including braces extending from the strip, and connecting links therefor.

4. An adjustable ruler of the character described including a flexible strip, right-angled members secured to the ends thereof, an indicating bar, one member being pivotally secured to one end of the bar, a slide adjustably mounted on said bar, means pivotally securing the other member to said slide, and means for maintaining the curvature of the strip in adjusted position, including braces extending from the strip at spaced points, links connecting the braces, and means for holding the links and braces in adjusted position.

Signed at Duluth, Minnesota, this 28th day of April, 1931.

JEAN ARAS.
